[57] **ABSTRACT**

A lateral edge of a bulk bin is pivotally mounted on the subjacent side edge of a flat bed trailer, thereby enabling the bin contents to be dumped laterally as the nether side of the bin is elevated. The pivot pin extends the entire length of the bin and projects fore and aft therefrom. The pin is journaled in a sleeve mounted centrally on the side edge of the flat bed, whereas the bin is hinged to the pin along substantially the entire length of the bin. The "floating" fore and aft extensions of the pin and adjacent corners of the bin are constrained in their vertical motion by snubbing means mounted on the ends of the flat bed and attached to the pin extensions. Selectively operable latch means hold down the nether corners of the bin.

BOX HOLD DOWN SYSTEM

The invention relates to improvements in trailer-mounted systems for attaching, transporting and emptying bulk bins of the side delivery type.

The patent literature, as well as the market place, is replete with devices capable of dumping boxes carried by a truck or trailer, both being termed a trailer, for convenience herein.

The rapidly expanding field of bulk bin hauling, with its attendant economies of operation, has led to a proliferation of trailer-bulk box combinations.

Owing to the fact, however, that trailers are normally constructed with a central upwardly convex bow, unique problems are presented when bulk bins are pivotally mounted fore and aft along one of the side edges of a trailer so as to afford side dumping capabilities. The convex bow, in a fore and aft direction, is built into the frame so that when the trailer is loaded to its customary capacity, the extent of the upward bow (amounting in unloaded condition to approximately 5% inches at the transverse mid-plane of the flat bed) will decrease to about zero. By so constructing the trailer, a negative deflection, or swayback, is obviated when the trailer is fully loaded. The bins, or boxes, supported on the trailer beds are large in size (for example, 8 feet $\times$ 5 feet $\times$ 24 feet) and must be capable of dealing with bulk cargo amounting to many tons. Since the bulk containers possess very considerable beam strength and rigidity, the extent of relative vertical flexure, or movement, between the flat bed and the customary bulk container between loaded and unloaded conditions is often very substantial. Thus, the side edge hinges heretofore utilized to hinge the box to the bed, particularly the hinges at the forward and after corners, have been subject to great stresses, quickly leading to rupture of the fastenings holding the respective hinge members to the relatively moving bed and bin as repeated cycles of loading and unloading occur. Rupture producing stresses have also occurred at the corner hinges when the nether side of the bin is lifted with the crane hook off-center in a fore and aft direction.

Efforts have heretofore been made to reduce the extent of stress imposed upon the bolts, rivets or other fasteners holding the hinged bin and bed together. These attempts, for the most part, have involved the elimination of the hinge connections adjacent the forward and after corners of the flat bed and the superposed box. However, when hauling over uneven terrain or when traveling at considerable speed along a bumpy roadway, very destructive buffeting of the box floor against the underlying ends of the flat bed can occur when the corners are not held down, particularly under circumstances giving rise to resonant vibrations.

It is therefore an object of the invention to provide a box hold down system which substantially eliminates both the rupture of hinge connections as well as the bouncing and buffeting which has heretofore taken place as a box is loaded and deflected from its initial position relative to the supporting flat bed of a truck or trailer and is thereafter transported to its destination in loaded condition and returned therefrom in unloaded condition.

It is a further object of the invention to provide a box hold down system which is not only relatively economical, both as to installation and upkeep, but which also is rugged, durable and long lived.

It is yet a further object of the invention to provide a box hold down system which is quickly and easily installed and operated, even by relatively unskilled personnel, yet is safe and reliable.

5 It is another object of the invention to provide a box hold down system which minimizes shock and substantially eliminates any vibration of a harmful nature either to the trailer, the bin or the cargo.

10 It is still another object of the invention to provide a box hold down system which is compact, readily serviced and does not unduly protrude beyond the margins of the bin and trailer combination.

15 It is another object of the invention to provide a generally improved box hold down system.

15 Other objects, together with the foregoing, are attained in the embodiment described in the following description and shown in the accompanying drawings, in which:

20 FIG. 1 is a left rear perspective view showing a typical installation of a bulk container pivotally mounted on a flat bed trailer for side delivery of the contents, the container being shown in lowered position;

25 FIG. 2 is a fragmentary perspective view, to an enlarged scale, of the hinge structure shown in FIG. 1;

25 FIG. 3 is a fragmentary sectional view, to a greatly enlarged scale taken through one of the two aligned hinge sleeves mounted on a side edge of the trailer body, the plane of the section being indicated by the line 3-3 in FIG. 2;

30 FIG. 4 is a fragmentary sectional view, to a greatly enlarged scale, taken through the central hinge collar mounted on a lateral lower edge of the box, the plane of the section being indicated by the line 4-4 in FIG. 2;

35 FIG. 5 is a fragmentary sectional view, to a greatly enlarged scale, taken through one of two aligned hinge rings mounted on the deflector gate, the plane of the section being indicated by the line 5-5 in FIG. 2;

40 FIG. 6 is a fragmentary sectional view, to a greatly enlarged scale, taken through a typical portion of the hinge pin, the plane of the section being indicated by the line 6-6 in FIG. 2;

45 FIG. 7 is a fragmentary left rear perspective view comparable to FIG. 1 but showing a shock absorber installed on the hold down arms and disclosing the gate in open position;

50 FIG. 8 is a fragmentary sectional view, to a greatly enlarged scale, of the snubbing mechanism, taken on the plane indicated by the line 8-8 in FIG. 7;

55 FIG. 9 is a fragmentary right rear perspective view;

FIG. 10 is a fragmentary rear elevational view, to an enlarged scale, of the pneumatically operated bin locking mechanism shown in FIG. 9, with portions of the figure broken away to reveal underlying details;

55 FIG. 11 is a fragmentary perspective view, to an enlarged scale, of the crane lifting hook ring in base position as appears in FIG. 9, the ring being supported on the actuating arm of the air valve;

60 FIG. 12 is a fragmentary perspective view, to an enlarged scale, of the right hand one of the rigging anchors shown in FIG. 9, the left hand anchor being a mirror image thereof;

65 FIG. 13 is a fragmentary perspective view, to an enlarged scale, of the center anchor of the crane rigging;

FIG. 14 is a rear elevational view showing the bin in a typical elevated position, preparatory to being returned by the crane to lowered, or base, position;

FIG. 15 is a diagram of the pneumatic bin latching system showing the air supply, air valve and pneumatic cylinder.

While the box hold down system of the invention is susceptible of numerous physical embodiments, depending on the environment and requirements of use, substantial numbers of the herein shown and described embodiment have been made, tested and used, and all have performed in an eminently satisfactory manner.

The box hold down system of the invention, generally designated by the reference numeral 16, connects an elongated bulk cargo bin 17 to the body 18, or chassis, of a trailer 19, or truck, supported on ground engaging wheels 21 and including, in the trailer shown in FIG. 1, a pair of front support posts 22. When in use, the forward end of the trailer would be supported on a truck fifth wheel, or comparable structure, not shown.

The bin 17 is strongly constructed of conventional frame members, such as angles and channels, with panels of plywood attached thereto, forming (see FIG. 1), a forward wall 24, an after wall 25, a left sidewall 26, a right sidewall 27 and bottom 28. The left sidewall 26 is hinged at the top to a hinge 30 on an upper fore and aft box channel 20, and the wall 26 can, if desired, be divided into two or more separately swingable portions, or doors.

The bottom 28 of the bin 17 is supported on the flat bed 31 of the trailer body, with the bottom margins of the box in substantial register with the subjacent margins of the trailer. That is to say, the lower, left-hand lateral edge 32 of the bin 17 immediately overlies the subjacent fore and aft lateral side 33 of the flat bed 31, and the after transverse lower edge 34 of the bin overlies the after end 35 of the subjacent flat bed 31. In like fashion, the opposite side edge 36 and forward edge 37 of the box 17 overlies the corresponding right-hand side edge 38 and forward edge 39 of the flat bed, as shown.

The lower left-hand lateral edge 32 of the bin 17, as in FIG. 1, is pivotally mounted on the lateral side 33 of the flat bed by a fixed hinge, generally designated by the reference numeral 41, the hinge 41 being located approximately midway between the opposite ends, as appears most clearly in FIGS. 1 and 2. The central hinge 41 includes an angle iron 42 (see FIGS. 2 and 3) secured, as by bolts 43 to the upper corner of a fore and aft channel 44 forming the lateral side edge 33 of the flat bed 31. Mounted on the horizontal flange 45 of the angle iron, as by welding, is a pair of aligned, spaced, fore and aft sleeves 46.

Journaled in the two fixed hinge sleeves 46 is a fore and aft pivot pin 47, or hinge pin, extending the entire length of the box 17, and the underlying flatbed 31. The pin 47 also somewhat protrudes beyond the ends of the box in both a fore and aft direction. The forward extension 48 and the after extension 49 of the pivot pin 47 are journaled, respectively, in a forward bearing 50 and an after bearing 51.

Loosely encompassing the pin 47 is a central collar 52 welded to a frame channel of the adjacent side panel 26, thereby hinging the box for pivotal movement relative to the flat bed. The pin 47 can be a heavy rod or a strong pipe.

The bearings 50 and 51 are "floating" in the sense that they are vertically movable within a limited arc whose radius is defined, in the case of each bearing, by a spaced pair of radius arms 53 secured at their distal ends to the respective one of the journal bearings 50 and 51 (each journal bearing being a mirror image of the other). The arms 53 are mounted at their proximal ends on the extremities of a hollow cross-shaft 54 snugly gripped by a resilient, high-friction bushing 56 of elastomeric material. The bushing 56, in turn, is tightly confined within a shell 57 (see FIG. 8) secured by fastenings 58 to a bracket 59 mounted on the after sides of a horizontal transverse upper channel 61 and a transverse lower channel 62 mounted on the transverse end channel 60 of the flat bed 31.

By frictionally resisting rotation of the cross-shaft 54, the radius arms 53 are constrained to oppose and move slowly in response to any forces tending to displace the pivot pin 47 vertically upwardly or downwardly. Also, tending to resist upward movement of the distal ends of the radius arms is a shock absorber 66, or leveler, (see FIGS. 7 and 8). The leveler 66 is pivotally mounted at its lower, distal end on a clevis 67 depending from the lower portion of the bearing 51 and pivotally mounted at its upper, proximal end on a clevis 68 mounted on and upstanding from the bushing shell 57.

Thus, although both the forward end and the after end of the pivot pin 47 are not constrained by a fixed hinge, such as the rigid center hinge 41, the combination of the downward force exerted at each end of the pivot pin by the respective levelers 66 and the frictional resistance provided by the elastomeric bushings 56, is effective to prevent the end portions of the bin 17 from vibrating and striking against the subjacent flat bed surface.

A first collar 71 mounted on the bin 17 loosely encircles the pivot pin 47 adjacent the forward bearing 50 and a similar collar 71 is provided adjacent the after bearing 51. The collars 71 serve to connect the two "floating" adjacent ends of the bin to the pivot pin 47 while the main central hinge 41 secured to the flat bed rigidly maintains the central portion of the bin in fixed vertical position relative to the bin while simultaneously allowing the bin to pivot about the hinge pin 47 as the bin is emptied. The two collars 82 augment the collars 71.

By thus allowing the fore and aft ends of the pivot pin 47 to "float," the adjacent end portions of the bin can deflect vertically upwardly and downwardly relative to the central portion of the box when loading and unloading of the bin contents takes place. Hinge rupture is thereby obviated. In other words, by allowing the ends of the box and the pivot pin to "float" relative to the trailer ends, no disruptive forces occur as a result of relative displacement occasioned by loading and unloading. At the same time, the hold-down effort exerted on each end of the box by the levelers, and the cushioning effect of the frictional elastomeric bushings maintains control over the "floating" ends of the pivot pin and the box, thereby obviating vibration and harmful buffeting against the subjacent portions of the flat bed.

The lower portion of the left-hand side panel 26 of the box includes a deflector gate, generally designated by the reference numeral 74 including an elongated plate 76 welded to a top longitudinal element of the pivot pin 47. The upper margin of the plate 76 is bent

outwardly to form a lip 77 and at the opposite ends of the gate a pair of sector plates 78 overlying the end panels 24 and 25 and suitably latched operating levers 79 are mounted. The somewhat laterally yielding levers are releasably held by cam faced latch plates 80 (see FIGS. 1, 2 and 7) on the near corner posts of the bin.

The gate 74 is welded to the pivot pin 47, as appears most clearly in FIG. 6, and includes a pair of rings 81 interposed between the sleeves 46 and the central collar 52. The bottom of the plate 76 is provided with a plurality of suitable accommodating apertures 83 to allow the central collar 52 and the collar pairs 71 and 82 encompassing the pin 47 to protrude through the plate and be connected to the adjacent fore and aft box channel. A comparable pair of apertures 84 in the plate 76 (see FIG. 3) allows relative motion between the pin 47 and plate 76 structure and the fixed sleeves 46. If preferred, the gate 74 can be hinged to the pivot pin 47 by omitting the weldments between the pin 47 and the gate 74, as indicated in FIG. 6, thereby allowing relative angular movement between the pin 47 and the loosely encompassing rings 81 secured to the gate 74, as appear most clearly in FIG. 5.

The gate 74 enables the contents of the box to be discharged through an elongated fore and aft opening 86 in the bottom portion of the left-hand side panel 26 (see FIG. 7) covered by the gate 74 when the gate is closed. When the contents are to be discharged, the nether, or right-hand, side of the bin is suitably elevated, as will be explained subsequently in more detail, and the hinged gate 74 is opened by unlatching and appropriately manipulating the operating levers 79. The plate 76 of the gate 74, when in open position, serves as a deflector apron, directing the bin contents laterally outwardly, well beyond the lateral side edge of the trailer and the supporting wheels. This feature is particularly valuable where the contents are of a soft nature, such as peaches or tomatoes, which are preferably kept out of the path of the trailer to avoid slippery conditions. When the box is elevated, the hinged side panel 26 also swings outwardly, by force of gravity, pivoting about the hinge 30. The open gate 74 and the side panel 26 form a converging channel 40 effective to guide the emerging contents in a lateral direction (see FIG. 14).

As will be appreciated, it is not only desirable that the ends of the box on the hinge side (left-hand side in FIG. 14) be free, within limits, to "float," but also that the nether, or right-hand side be provided with somewhat similar capabilities. Thus, even though the right-hand side of the box is locked down during all conditions except unloading, by suitable lock mechanisms now to be described, both the forward and the after ends of the box on the right-hand side can move, within small limits, and under constraint, relative to the subjacent portions of the flat bed.

Locking engagement between the nether corners of the bin and the flat bed is effected, at each end, by a latch mechanism 86 (see FIGS. 1, 9 and 10) comprising a rockable latch hook 87 pivoted on a pivot pin 88 and actuated by a pivotally-mounted plunger 89 in association with a pneumatic cylinder 90 of the kind used, for example, in connection with the air brakes of a motor vehicle.

When the plunger 89 is extended, the latch hook 87 partially encircles a pin type of latch detent 91, or latch

pin, protruding rearwardly from an angle iron 92 mounted on a transverse lower rear frame member 93 of the bin. The pin detent 91 is also secured at its after end to a downturned, L-shaped, member 94 projecting rearwardly from and connected to the angle iron 92 and the bin frame member 93.

The angle iron 92, the L-shaped bracket member 94 and the detent latch pin 91, in other words, are attached to the bin whereas the latch hook 87 is connected to the flat bed. Thus, when it is desired to lift the box into emptying position, the hook 87 is withdrawn from the latch pin 91 by retracting the plunger 89 into the cylinder 90.

This unlatching motion is automatically effected as 15 the crane hook rigging ring 96 is lifted off the vertically movable upwardly biased air switch 95 located just above the ring-supporting hook 97 (see FIGS. 9, 11 and 15), the switch 95 being connected to an air valve 98 interposed in an air supply line 99 extending from a 20 pressurized air tank 101 to the pneumatic cylinder 90.

The air valve actuator 95 is so connected to the air valve 98 that in the base position shown in FIGS. 9 and 11, the weight of the ring 96 and attendant wire cables 25 103, leading from the central lower anchor 104 and extending angularly downwardly to the forward anchor 106 and after anchor 107, is sufficient to overcome upward bias and depress the valve actuating switch 95 so as to keep the air valve 98 in open or locked position. 30

When it is desired to tilt the bin into unloading position, however, and the crane hook ring 96 is lifted off the vertically movable, spring-loaded valve actuator 95 and supporting hook 97 in order to attach the lifting ring 96 to the crane hook 111 (see FIG. 14) the spring-loaded valve actuator 95 moves upwardly, allowing the spring-loaded air valve 98 to close so as to release the actuating air pressure on the plunger 89 and allow the internal return spring (not shown) to act and thereby 40 unlatch the hook 87 from the latch pin 91.

After the hook 87 is thus unlatched, the crane hook 111 is attached to a lifting crane by which the bin can be elevated, thereby lifting the nether side of the bin and tipping the bin and allowing the contents to spill out through the channel defined by the deflector gate 74 (previously or concurrently opened) and the gravity actuated door 26. The channel formed by the door 26 and the gate permits dumping of the contents without unduly tilting the bin and also deflects the contents laterally, well clear of the discharge side of the trailer. 50

After the contents are emptied, the crane hook is again lowered so that the bin can settle back into position on the flat bed. The crane hook ring 96 is thereupon removed from the crane hook 111 and returned to the valve actuator 95 and attendant support hook 97, the weight of the rigging depressing the actuating lever 95, thereby causing the air valve to open and translating the plunger 89 so as to return the latch hook 87 into hold-down engagement with the detent pin 91, thereby completing the cycle. 60

As appears most clearly in FIG. 10, the latch hook face 100 in engagement with the detent pin is so shaped that the air pressure on the latch hook tends constantly to cam or bias the hook 91 in a downward direction. In other words, the inner curvature 100 of the latch hook 87 is such that the strong pneumatic force urging the latch hook 87 into engagement with the latch pin 91

tends to force the latch pin 91 downwardly, thereby resisting upward bouncing movement of the adjacent box corner. Yet, owing to the hook curvature, some slight freedom is afforded so that the latch hook 87 can move up and down to a small degree, with respect to the relatively small vertical reciprocations of the latch pin 91. Rupture of the engaging members is thereby obviated. This same yielding resistance to relative movement also prevents rupture as loading and unloading of the cargo takes place.

It can therefore be seen that we have provided a box hold down system for use with a bin-trailer combination which is not only capable of eliminating the vibration and structural ruptures heretofore encountered, but which is also safe, efficient, economical and long lived in operation.

What is claimed is:

1. In combination with a trailer including a flat bed with a pair of fore and aft side edges and a pair of transverse ends, a box hold down system comprising:

- a. a hinge carried on one of said side edges, said hinge including a sleeve mounted on said one of said side edges intermediate said ends of said trailer, and a pivot pin journaled in said sleeve and extending longitudinally adjacent said one of said side edges of said flat bed;
- b. a box supported on said flat bed in a first lowered position, the lateral edge of said box adjacent said one of said side edges being pivotally connected to said hinge, said pivot pin extending longitudinally adjacent said lateral edge of said box, said box being pivotally mounted on said pin and angularly movable between said first lowered position and a second elevated position laterally to discharge the contents of said box;
- c. snubbing means mounted on said transverse ends adjacent said one of said side edges and connected to the adjacent corners of said box for resiliently opposing the upward movement of said lateral edge of said box, said pin including a forward extension and an after extension projecting beyond the respective forward end and after end of said flat bed, said pin extensions being connected to said snubbing means; and,
- d. latch means mounted on said ends of said flat bed adjacent the other of said side edges and connected to the adjacent corners of said box for detachably holding down said box.

2. A box hold down system as in claim 1 in which said snubbing means includes a bushing of resilient material having a high coefficient of friction, a shaft rotatably mounted on said bushing in frictionally resistant engagement therewith; a lever arm mounted at one end on said shaft and pivotally connected at the other end to the adjacent one of said pin extensions.

3. A box hold down system as in claim 2 including a spring biased leveler adjacent each of said snubbing means, one end of said leveler being mounted on the adjacent of said transverse ends and the other end of said leveler being mounted on the adjacent of said pin extensions.

4. A box hold down system as in claim 1 in which said latch means includes a latch detent on each of said adjacent corners of said box; a latch hook pivotally mounted on said ends of said flat bed adjacent said other of said side edges for selective engagement with and disengagement from said detent; and pneumatic

means for selectively connecting and disconnecting said latch hook from said latch detent.

5. A box hold down system as in claim 4 wherein said pneumatic means includes a plunger pivotally connected to said latch hook; a pneumatic cylinder operatively engaging said plunger; a pressurized air supply connected to said cylinder; and valve means connected to said air supply for remotely controlling the operation of said cylinder and said plunger to effect latching and unlatching of said hook.

6. A box hold down system as in claim 1 in which one side of said box includes a gate extending along said lateral edge of said box, said gate being connected to said pivot pin.

15 7. A box hold down system as in claim 6 wherein said gate includes a fore and aft elongated plate mounted on said pivot pin; and a gate operating lever mounted on said pin, said lever being capable of swinging said gate between a closed position covering an elongated opening in the bottom of said one of said walls adjacent said lateral edge of said box and an open position uncovering said opening.

20 8. A box hold down system as in claim 6 including a door hingeably mounted on said one side of said box, said door being capable of opening outwardly by gravity and forming with said gate in said open position a laterally outwardly converging cargo channel.

9. In a trailer having a flat bed with a pair of fore and aft side edges and transverse ends, a system for holding down a box carried on the trailer comprising:

- a. a hinge mounted on one of the side edges of the flat bed substantially centrally between the transverse ends, one lateral edge of the box being connected to said hinge for tilting movement between a first lowered position and a second elevated position, the corners of the box located fore and aft from said hinge being sufficiently remote from said hinge as to be substantially responsive to forces tending to move the box corners vertically relative to the subjacent flat bed during use of the trailer;
- b. snubbing means mounted on the trailer and connected to the box for resiliently opposing movement of said box corners; and
- c. latch means mounted on the trailer and connected to the box for detachably securing the other lateral edge of the box to the flat bed.

10. A box hold down system as in claim 9 in which said latch means includes a latch detent mounted on the box, a latch hook pivotally mounted on the flat bed adjacent the end of said other lateral edge of the box for selective engagement with and disengagement from said detent, and means for selectively connecting and disconnecting said latch hook from said latch detent.

11. A box hold down system as in claim 9 including a door hingeably mounted along the upper portion of the side of the box adjacent said hinge, said door being capable of opening outwardly to provide a channel for the discharge of cargo as the box is tilted upwardly from said first lowered position toward said second elevated position.

12. A box hold down system as in claim 9 in which the side of the box adjacent said hinge includes a gate extending along said one lateral edge of the box, said gate being movable between a closed position covering an elongated fore and aft opening along the lower portion of said box side and an open position uncovering said opening.

13. A box hold down system as in claim 9 in which said hinge includes a sleeve, and a pivot pin journaled in said sleeve and extending fore and aft along said one lateral edge of the box to a location adjacent said corners, the box being pivotally mounted on said pin adjacent said sleeve and adjacent the ends of said pin, the ends of said pin being connected to said snubbing means adjacent said corners for resiliently opposing

relative vertical movement between said corners and the underlying surface of the flat bed.

14. A box hold down system as in claim 13 including a shock absorber mounted on at least one end of the trailer and connected to the adjacent end of said pin, said shock absorber being inclined at an attitude such as to oppose upward vertical movement of said pin.
